(57) **CLAIM**

The ornamental design for a charging dock as shown and described.

DESCRIPTION

FIG. 1 is a perspective view of a charging dock showing our new design;

FIG. 2 is front view thereof;

FIG. 3 is a back view thereof;

FIG. 4 is a side view thereof;

FIG. 5 is another side view thereof;

FIG. 6 is a top view thereof;

FIG. 7 is a bottom view thereof; and,

FIG. 8 is another perspective view thereof depicting one or more batteries as environmental subject matter.

The broken lines shown in the drawings illustrate portions of the charging dock that form no part of the claimed design.

1 Claim, 5 Drawing Sheets
